MAURICE BOUCHET, OF PARIS, FRANCE.

MARINE SAFETY DEVICE.

1,086,989.

Specification of Letters Patent.

Patented Feb. 10, 1914.

Application filed July 20, 1911. Serial No. 639,607.

To all whom it may concern:

Be it known that I, MAURICE BOUCHET, of 22 Rue Alphonse de Neuville, in the city of Paris, Republic of France, a citizen of the 5 French Republic, have invented a Marine Safety Device, of which the following is a full, clear, and exact description.

My invention relates to marine safety devices, my more particular object being to 10 provide for increasing the buoyancy of the vessel at certain critical times when danger may accrue from undue pressure of water outside of the vessel, thus tending to crush the vessel inwardly, or from excessive air 15 pressure inside of the vessel, having a tendency to disrupt the vessel or some portion thereof.

My invention is associated with the use of 20 water-tight compartments used for ballasting the vessel with water, or to compartments containing machinery of any kind and into which water may, by accident or otherwise, be admitted.

In connection with my invention, I employ 25 one or more tanks of compressed air as hereinafter described, and mechanism acted upon by the pressure of air from said tanks, to liberate a quantity of compressed air within the compartment or compartments to 30 be evacuated, so that the pressure of the compressed air expels the water.

My apparatus is so arranged that when 35 accidents of certain kinds happen so as to admit water into certain compartments of the vessel, my apparatus is actuated automatically to open a tank of compressed air, said tank having such capacity that the compressed air contained within it is of sufficient quantity to expel or drive back the 40 water entering the compartment, or the water contained in the various water ballasted compartments, of the ship. Moreover, this device comprehends automatically actuating special protective or life-saving apparatus, 45 such as those insuring the releasing of the safety weights and telephonic buoys, the closing of the water-tight doors, etc.

My device is essentially characterized by 50 the application, in a compartment communicating with the compartment to be protected, of a manometric device, such as a flexible diaphragm, upon which acts the super-pressure which is produced when the water breaks into the ship. This diaphragm is 55 combined with a mechanism which opens the high pressure air tank, the compressed air

being sent either in the compartment itself, or in one or more water-ballasted compartments, or to a cylinder for operating a piston which actuates a releasing or other mechanism.

My device is also characterized by a pressure balancing mechanism which automatically closes the air tank when a certain degree of pressure is reached; this pressure is 65 sufficient for insuring the exhaustion of the water. This balancing mechanism avoids a dangerous and unnecessary increase of pressure and prevents the tank from getting completely empty.

The invention is illustrated, by way of example, in the accompanying drawings, in which;

Figure 1 shows in longitudinal vertical section an operating device applicable to a 75 submarine or submersible boat; Fig. 2 is a fragmentary vertical section somewhat similar to Fig. 1, but showing various movable parts as occupying positions different from those they occupy in said figure; Fig. 3 is a 80 section somewhat similar to Fig. 2, but showing the device in action and the parts occupying different positions.

As will be seen in Fig. 1 of the drawings, the present device comprises a casing *a*; the 85 bottom of said casing is connected by a pipe *a'*, provided with a valve *a''*, to a water-tight compartment *u*. To this bottom is also connected a pipe *b'* the function of which will be described hereafter. Inside the casing *a* is arranged a metallic diaphragm *c* provided at its center with a rigid part *c'*. This diaphragm is subjected, on the one hand, to the pressure coming from the compartment by 90 the pipe *a'*, and, on the other hand, to the pressure existing in a bell *d*. From this bell *d* leads a pipe *d'* in which a cock *d''* is placed at a suitable place, for instance at the commander's station, the said pipe ending in the casing *a*. The diaphragm *c* is guided by a rod *e* and it actuates, through the medium of connecting rods *f* and *g* and of a lever *h* pivoted at *h'*, a piston *l* controlling the opening mechanism of the compressed air tank *l'* which is thus arranged so as to let the air escape more or less rapidly, according to the pressure inside the casing *a*. On the other hand, at right angles to the diaphragm *c* is arranged a second 100 flexible diaphragm *m* having a disk shaped rigid part *m'*; this diaphragm *m* is located

2

between the casing *a* and a tank *n* communicating by a pipe *n'* with the atmosphere, at a point where the pressure is the same as that which acts outside the water ballasted compartment; in these conditions the diaphragm *m* is subjected, on the one hand, to the pressure existing inside the compartment and, on the other hand, to the pressure at the point thus chosen. The rigid part *m'* of the disk *m* normally rests on a circular resilient abutment *o*. This arrangement prevents any introduction of liquid into the compartment to be protected, if the flexible part of the diaphragm becomes distorted.

15 The said diaphragm is guided by a rod *p* in contact with a spring *p'* and it is connected by a link *q* to the connecting rod *f*.

The operation is as follows:—Normally, the various parts of the device are in a state 20 of equilibrium, as illustrated in Fig. 1. If, by reason of an accident, the water breaks into the compartment of the ship, a super-pressure is produced in this compartment and being transmitted through the pipe *a'* and acts upon the diaphragm *c*. If, at this moment the cock *d'* is closed, which controls the bell *d*, the diaphragm is then driven upwardly and through the medium of the connecting rods *f* and *g* and of the lever *h*, 25 acts upon the piston *l* of the compressed air tank *l'*, as illustrated in Fig. 2. This air under pressure then enters the compartment *u* through an orifice *l''* and a pipe *l'''* and tends to drive back the water that has entered 30 therein. When by reason of the admission of compressed air the pressure of the air inside the compartment *u* and consequently at *a* becomes greater than the pressure at *n*, the diaphragm *m*, through the medium of the link *q*, acts on the connecting rods *f* and *g* and on the lever *h* which moves, thus releasing 35 the piston *l*. The diaphragm *m* can therefore control the closing of the tank *l'* independently of the diaphragm *c* which remains lifted. If the pressure at *n'* again becomes the strongest, the device *m q* comes back to its initial position, thus allowing the 40 opening or closing of the tank *l'*, according to the position occupied by the diaphragm *c*.

45 The device illustrated presents this advantage that it comprises connecting rods only, to the exclusion of cams and springs which may, in the course of time, deteriorate.

50 The air issuing from the tank *l'* through the orifice *l''* is sent either directly in the compartment of the ship or to a cylinder *x* for actuating any mechanism whatsoever. A hand wheel *l'* allows the opening or closing 55 by hand of the tank *l'*. This hand wheel may be used as a safety device for preventing any blockage of the device. The cock *d'* serves to prevent at will the automatic operation of the device. It has the advantage, when it is open, of balancing the pres-

sure on the two faces of the diaphragm *c* and of thus compensating the accidental superpressure. The spring *p'* produces the necessary pressure for obtaining the displacement of the diaphragm *m* and consequently the stoppage of the discharge of compressed air.

The present automatic device may be used for operating, in the ordinary ships, the safety apparatus, for instance the water-tight doors. In this case, the piston *x'* 75 can actuate the rack *x''* of these water-tight doors. In submarine boats it is possible to actuate by this means the safety apparatus, such as those insuring the releasing of the 80 safety weights, telephonic buoys, etc. A pipe *t* leads to one or more operating stations situated at various places on the vessel. Each of these stations is composed of a small tank *r* containing air compressed under a small pressure and a cock *r'* which is always held closed by a spring. If the cock 85 of one of these stations is opened, the air contained in the tank *r* is sent, through the pipe *t* to the casing *a* and the pressure of this air is sufficient for actuating the diaphragm *c* as previously described. Therefore it will be possible to operate from any place of the ship the water-tight door or any device whatsoever. It is to be noted 90 that the pipe *t* is submitted to an insignificant pressure only and that it can have a very small diameter. A valve *t'* renders this device independent of the other parts.

A single cock *r'* can control several 100 devices similar to that described and corresponding to an equal number of compartments or mechanisms to be operated.

Having thus described my invention, what I claim as new and desire to secure by Letters Patent is as follows:—

1. In a safety device for ships and submarine boats, the combination of a casing, a diaphragm mounted therein, a water-tight compartment communicating with said casing, a series of levers connected with said diaphragm, a compressed air tank, a pipe leading from said compressed air tank to said water-tight compartment, means controllable by said series of levers for opening said compressed air tank, a second casing connected with said first mentioned casing, a diaphragm located in said second mentioned casing and exposed to pressure of air from said first mentioned casing, and an 110 operative connection from said second mentioned diaphragm to said series of levers for the purpose of closing said air tank.

2. A device of the character described, comprising a casing, a diaphragm mounted 115 therein, a water-tight compartment communicating with said casing for the purpose of actuating said diaphragm, a compressed air tank for discharging air into said water-tight compartment, means for normally 120

130

maintaining said air tank closed, a series of levers connected with said means for actuating the same in order to open said air tank, a diaphragm connected with said series of levers for actuating the latter in order to open said compressed air tank, a spring pressing upon said last mentioned diaphragm, a casing inclosing said last mentioned diaphragm and communicating with 10 said first mentioned casing for the purpose of subjecting said last mentioned diaphragm to air pressure from said first mentioned casing, and a link connecting said last mentioned diaphragm with said series 15 of levers.

3. In a safety device of the character described, a casing, a diaphragm mounted therein, a water-tight compartment, a pipe leading from said water-tight compartment 20 to said casing, a compressed air tank, a pipe leading from said compressed air tank to said water-tight compartment, a series of levers connected with said diaphragm and provided with means for opening said air 25 tank, a second diaphragm connected with said series of levers for the purpose of actuating the same in order to close said air tank, said second mentioned diaphragm being controllable by excess of air pressure within 30 said casing due to the opening of said compressed air tank, an operative connection from said second mentioned diaphragm to said series of levers in order to enable a movement of said second mentioned dia- 35 phragm to close said air tank.

4. A device of the character described, comprising a casing, a diaphragm mounted therein, a water-tight compartment communicating with said casing, a cover located 40 on one side of said diaphragm in order to provide a clearance space for movements thereof, a pipe connected with said cover and communicating with the clearance space, means controllable at the will of the operator 45 for opening and closing said pipe, a compressed air tank, a pipe leading therefrom to said water-tight compartment, a series of levers connected with said diaphragm, means controllable by said series of levers for dis- 50 charging compressed air, a second casing communicating with said first mentioned casing, a diaphragm mounted within said second mentioned casing and exposed to pressure of fluid tending to travel from said 55 first mentioned casing into said second mentioned casing.

5. A device of the character described, comprising a casing, a diaphragm located within said casing, a water-tight compartment connected with said casing, a second casing communicating with said first mentioned casing, a diaphragm located in said second mentioned casing, lever mechanism 60 common to both of said diaphragms and controllable thereby, a compressed air tank, 65

a connection from said compressed air tank to said water-tight compartment, and means controllable by said lever mechanism for opening and closing said compressed air tank.

6. A device of the character described, comprising a casing, a water-tight compartment, a pipe connecting said casing with said water-tight compartment, a valve at the inlet end of said pipe, a diaphragm in 70 said casing, a series of levers connected with said diaphragm, a compressed air tank, a pipe leading from said compressed air tank to said water-tight compartment, means controllable by said levers for opening said 75 tank, a second diaphragm, said second dia- phragm being so located as to be subjected to pressure of a fluid within said casing, and a connection from said last mentioned dia- phragm to said levers.

7. In a safety device for ships and submarine boats, the combination of a casing, a diaphragm mounted therein, a water-tight compartment connected with said casing, a compressed air tank, a pipe leading from 80 said compressed air tank to said water-tight compartment, a closure member for opening said air tank, a series of levers connected with said closure members in order to actuate the latter, a second diaphragm so located 85 as to be exposed to air pressure within said casing, and an operative connection from said last mentioned diaphragm to said series of levers for the purpose of actuating the latter in order to open said compressed air 90 tank.

8. In a safety device for ships and submarine boats, the combination of a casing, a diaphragm mounted within said casing, a water-tight compartment, a compressed air tank, a closure member for normally maintaining said compressed air tank closed, a series of levers connected with said dia- 105 phragm and with said closure member for the purpose of actuating said closure mem- 110 ber and thus opening said compressed air tank, a connecting rod from said compressed air tank to said water-tight compartment in order to discharge compressed air into said water-tight compartment when said compressed air tank is opened, a pipe leading from said water-tight compartment to said casing, a check valve connected with said pipe and opening into said casing, a second dia- phragm located in said casing and connected with said series of levers, a cover for 115 said diaphragm and means for admitting a fluid under pressure into said cover for the purpose of actuating said last mentioned dia- phragm.

9. In a safety device for ships and submarine boats, the combination of a casing, a diaphragm connected therewith, a water- 120 tight compartment connected with said cas- ing, a compressed air tank for discharging 130

air into said water-tight compartment, a pipe leading from said water-tight compartment to said casing, a member for opening said compressed air tank, a series of levers, 5 for actuating said member, a second diaphragm, said second mentioned diaphragm being exposed to pressure of air within said casing, means for exposing said last mentioned diaphragm to pressure opposing the 10 air pressure thereagainst, and an operative connection from said last mentioned diaphragm to said series of levers for the pur-

pose of actuating the latter in order to close said compressed air tank.

The foregoing specification of my device 15 for automatically actuating safety and raising apparatus, applicable to ships and to submarine boats, signed by me this seventh day of July 1911.
